BY *Victor J. Evans*

ATTORNEY

UNITED STATES PATENT OFFICE

HERMAN SCHULTZ, OF RACINE, WISCONSIN

PENCIL SHARPENER

Application filed August 5, 1929. Serial No. 383,738.

The object of this invention is to provide means for sharpening a pencil, said means including the usual cutting devices, but in this instance placed in operation by the act 5 of inserting the pencil in proper position,— and an electrically driven device having a circuit completed therethru, in the manner indicated.

A further object is to provide, in connection with a plurality of cutting or shaving devices, driven preferably by an electric motor, means in the motor circuit adapted to be operated for closing the circuit and starting the cutting devices without special attention 15 on the part of the individual making use of the device.

A further object is to provide a motor driven sharpening device which may if desired have means for completing the motor 20 circuit by manual operation, the circuit including a switch of any standard or well known type.

With the foregoing and other objects in view, the invention consists in the novel 25 construction and arrangement of elements disclosed, it being understood that modifications may be made within the scope of the claim without departing from the spirit of the invention.

30 In the drawings forming part of this application:—

Figure 1 is a view of the device in end elevation.

Figure 2 is a view in side elevation with 35 a portion broken away.

Figure 3 is a view in vertical transverse section, on line 3—3 of Figure 2.

Figure 4 is partly in top plan and partly in section, the section being on line 4—4 of 40 Figure 2.

Figure 5 is a diagrammatic view of the circuit for the motor, and the controlling means therefor.

Any suitable electrical motor may be employed 45 for the purpose herein indicated and in Figure 2 a motor illustrated conventionally is designated at 10, the armature shaft thereof being shown at 11. The shaft 11 of the motor imparts movement to the rotary cutting or shaving devices designated 16 and

17 and which are relatively spaced for receiving and sharpening a pencil.

The motor 10 has connected therewith the feed wire 20, and feed line 21 leads to the point 22 at the end of supporting element 23 secured at 24 on the housing 25. Element 23 carries a contact element on the lower end thereof, at 23', and this contact cooperates with contact element 24' mounted on a resilient bracket comprising the upright portion 26, and arms such as 27 between which rotatable device 28 is mounted. The bracket 26 is secured at 26' to bar or the like 29 and the latter is in turn secured within the housing 25 in the manner shown in Figure 3. 65

A bracket 30 corresponding with the bracket previously referred to, is mounted opposite the latter, and in a reverse position, so that the rotatable device 31 carried by bracket 30 will be in the position shown in 70 Figure 3 and the rollers 28 and 31 will receive therebetween a pencil to be sharpened, the resilient bracket 26 being adapted to move to the left in Figure 3, in order to close contacts 23' and 24', upon the insertion 75 of the pencil.

A wire 34 connects with contact 24', and is also connected with motor 10, whereby a circuit is completed thru the motor for the purpose of starting the latter automatically 80 upon the insertion of a pencil in position to be sharpened. It will thus be observed that the operator has nothing to look after in the way of starting the motor or discontinuing its operation, for the contacts will open automatically as soon as the pencil is withdrawn. 85

A pencil-supporting element 19 may be positioned as shown in Figure 4 in alignment with the space, between the cutters, to be occupied by the pencil when in position for 90 sharpening.

What is claimed is:—

A pencil sharpener including a support having spaced rotatable cutting elements driven by an electrical motor provided with 95 an electrical circuit connected to an electrical source, a transverse bracket secured to said support below the cutting elements, vertically disposed resilient arms carried by the bracket and arranged to receive a pencil 100

when inserted between the cutting elements and adapted to be flexed by said pencil, rollers journaled to said arms to be engaged by the pencil, and spaced resilient contacts in the circuit to normally break the latter and one contact secured to the support and the other contact carried by one of the resilient arms, said contact brought into engagement by the pencil flexing the last named arm when inserted between the cutting elements.

10 In testimony whereof I affix my signature.
HERMAN SCHULTZ.
